[57] CLAIM

The ornamental design for a wall mounted holder for
the arm of a copy stand or the like, as shown and de-
scribed.

DESCRIPTION

FIG. 1 is a front elevational view of a wall mounted
holder for the arm of a copy stand or the like showing
my new design;

FIG. 2 is a rear elevational view thereof;

FIG. 3 is a right side elevational view thereof, the left
side being a mirror image;

FIG. 4 is a top plan view thereof; and

FIG. 5 is a bottom plan view thereof.

The broken lines are shown for illustrative purposes
only and form no part of the claimed design.

FIG. 1.

FIG. 2.

FIG. 3.

FIG. 4.

FIG. 5.
